(57) **CLAIM**

The ornamental design for a graphical processing unit bracket as shown and described.

DESCRIPTION

FIG. 1 shows a top and side perspective view of a graphical processing unit bracket.

FIG. 2 shows a reverse bottom and reverse side perspective view thereof.

FIG. 3 shows a side elevation view thereof.

FIG. 4 shows a reverse side elevation view thereof.

FIG. 5 shows a second side elevation view thereof.

FIG. 6 shows a reverse side elevation view relative to the second side elevation view thereof.

FIG. 7 shows a top plan view thereof; and,

FIG. 8 shows a bottom plan view thereof.

The broken lines form no part of the claimed design and are used to show the environment only.
